UNITED STATES PATENT OFFICE.

CLINTON W. FORD, OF DETROIT, MICHIGAN.

DESIGN FOR A LAMP PEDESTAL.

Application filed November 7, 1922. Serial No. 4,236. Term of patent 3½ years.

To all whom it may concern:

Be it known that I, CLINTON W. FORD, a citizen of the United States, residing at Detroit, in the county of Wayne and State of Michigan, have invented a new, original, and ornamental Design for Lamp Pedestals, of which the following is a specification, reference being had to the accompanying drawing, forming part thereof.

I claim:—

The ornamental design for a lamp pedestal as shown.

In testimony whereof, I affix my signature

C. W. FORD.
